UNITED STATES PATENT OFFICE.

BERNHARD C. J. ANDERSON, OF MORTON PARK, ILLINOIS, ASSIGNOR OF ONE-HALF TO L. F. NONNAST, OF CHICAGO, ILLINOIS.

CARBURETER.

SPECIFICATION forming part of Letters Patent No. 637,062, dated November 14, 1899.

Application filed November 21, 1898. Serial No. 697,036. (No model.)

To all whom it may concern:

Be it known that I, BERNHARD C. J. ANDERSON, a citizen of the United States, residing at Morton Park, in the county of Cook and 5 State of Illinois, have invented a new and useful Improvement in Gas-Generators, of which the following is a specification.

My invention relates particularly to an improved generator for generating gas from 10 gasoline or other hydrocarbon oils of a like nature.

My object is to provide a generator of simple and inexpensive construction capable of gasifying oils of this nature under conditions 15 of perfect safety and capable also of insuring a sufficient pressure to raise the relatively heavy gas generated from such an oil to any desired height for consumption, thus enabling comparatively low-grade inexpensive oils to 20 be used, with consequent great saving of expense. I accomplish the desired results by means of the improved generator illustrated in the accompanying drawings. The generator comprises, generally stated, an elevated 25 oil-chamber which may be recharged from any suitable oil-reservoir, a discharge-pipe, preferably of upright U-shape form, communicating with said oil-chamber, a generator-burner toward the lower end of the rising portion 30 of said U-shaped pipe, provided with a chimney inclosing said rising portion of the pipe, a pipe leading from the upper portion of said oil-chamber to said burner and serving to conduct fumes arising from the oil, and 35 also generated gas, to said burner, and a service-pipe communicating with said rising portion of the U-shaped pipe, preferably supplied with means for mixing air with the gas before the service-burner is reached and with 40 means for collecting any oil or impurities carried over with the gas or any condensation from the gas itself and returning the collected oil to the oil-chamber.

In the accompanying drawings, Figure 1 is 45 a view in elevation and diagrammatic in its nature, showing my improved generator and its manner of installation; Fig. 2, a broken vertical section of the upper portion of the device, the section being taken on line 2 of 50 Fig. 6; Fig. 3, an enlarged sectional detail of

a needle-valve regulating the passage of gas from the generating-pipe toward the service-pipe, the section being taken at line 3 of Fig. 6; Fig. 4, a sectional detail of a valve regulating the passage of fumes and generated gas 55 from the oil-chamber to the generator-burner, the section being taken on line 4 of Fig. 6; Fig. 5, a plan section of the rising portion of the generator-pipe and the pipe-like chimney inclosing the same; Fig. 6, a general top plan 60 sectional view taken as indicated at line 6 of Fig. 2; Fig. 7, a broken detail of the pump employed for filling the oil-chamber, and Fig. 8 a detail of the generator-burner.

A represents an oil-chamber conveniently 65 supported on a hollow standard B, through which passes the descending portion *t* of a U-shaped pipe C in communication with the lower part of the chamber A. The rising portion *t'* of the pipe C is by preference incased 70 in a pipe D, serving as a chimney for a generator-pipe heater or burner E, supplied with a combustion-chamber E', inclosing the lower portion of the pipe *t'*.

The burner E is supplied with a perforated 75 burner-plate E² and beneath said plate with a fuel-supply pipe F, communicating with the chamber A above the oil-line. In the course of the pipe F is placed a needle-valve F', Fig. 4, adjusted by means of a pivotally-secured 80 handle F², moving on a dial-plate F³, supplied with notches *s* for the reception of a lug *s'* on said handle. The pipe F is supplied below the valve with air-inlets *r*, and preferably extends below its point of communication with 85 the burner, as shown, to aid in the production of a strong updraft through the burner at the instant of ignition. The combustion-chamber is supplied above the burner-plate with a door *q*, pivoted at its upper portion, 90 and preferably also with apertures *q'*, guarded by wire-gauze *q*².

The upper end of the pipe *t'* is joined to a valve-shell G, Fig. 3, supplied with a needle-valve G', operated by a hand-wheel G²; and 95 is also supplied with an index-pointer *p*, which has feather-and-groove connection with the spindle of the valve and is spring-held in contact with a dial G³, supported from the shell G. The shell G has screw connection with a 100

perforated plug H, which in turn screws adjustably into the end of a pipe H', disposed above and supported by the chamber A.

Within the pipe H' and located in close proximity to the port guarded by the valve G' is a short pipe I, which has gas-tight connection with an annular ring n on the interior of the pipe H'. Into the pipe I the gas issuing from the port at the valve G' passes with sufficient velocity to induce an air-current through a pipe J, leading from the adjacent part of the pipe H' to the exterior of the wall K of the building in which the generator is installed. The intake end of the pipe J is shown protected by a hood J'. A small drain-pipe m, having gas-tight connection with the pipe H', adjacent to the valve G', and with the top of the chamber A and extending to near the bottom of the chamber A, serves as a sealed return-channel to the chamber A for any particles of oil collecting at this point which may be carried through at the valve G'.

Beyond the pipe I the pipe H' has connection through a pipe L with the upper part of the chamber A. From the pipe H' the gas passes to a service-pipe M and any desired number of service lighting or heating burners M' through an interposed trap-supplied collecting device P. The device P comprises, preferably, an elbow-joint l, supplied with a trap l' and with an inner passage l², leading to a relatively short pipe l³, which projects upward from a diaphragm l⁴, and an enlarged pipe l⁵, which screws into the upturned portion of the elbow. A drain-pipe l⁶ extends from the diaphragm l⁴ to near the bottom of the trap l', and the passage l² is in communication with the trap l' through a passage l⁷. By this arrangement, it will be observed, the channel for the passage of gas is through the chamber l² and pipe l³, the pipe l⁶ being sealed by the first collection of liquid in the trap.

When service-burners sufficient to consume all the gas which is being generated are simultaneously in use, there is comparatively little condensation of gas within the system, the trap l' serving then merely to collect any water or other impurities present. If a number of the service-burners are thrown out of use while the machine is generating gas at its full capacity, however, the sluggish movement of the gas, with consequent opportunity for cooling, causes a larger condensation. In such case the condensed liquid fills the trap l', the water and other impurities settling to the bottom, where they are drawn off from time to time, and the oil rising through the opening l⁷ and returning through the pipe H' to the chamber A.

The gasoline may be stored in a tank N outside the building and raised to the chamber or head A through a pipe k by means of a pump N'. The pump is shown in detail in Fig. 7 and is of a well-known construction. An overflow-pipe h, communicating with the

chamber A a short distance below its top, prevents the oil-level from rising above the dotted line h'. (Shown in Fig. 2.)

The operation is as follows: A supply of oil is raised to the chamber A by means of the pump N', the agitation of the liquid being sufficient to cause fumes to pass through the pipe F and open valve F' and descend to the burner E, where they may be ignited through the door q. As the generating pipe or chamber t' becomes heated (supposing now the valve G' to be closed) gas collects in that portion of said pipe above the oil-level and gradually forces the oil back out of the generator portion of the U-shaped pipe. The liquid column in the pipe t is now balanced by gas-pressure in the pipe t', and if the valve G' be opened the gas will shoot through the pipe I and induce an air-current through the pipe J sufficient in volume to supply the desired quantity of oxygen. The gas will now rise in the pipe M (if unimpeded) till the gas column is of sufficient height to balance the liquid column or head in the pipe t and chamber A, it being borne in mind, of course, that the reduced orifice at the valve G' acts virtually as a pressure-reducing valve. In practice the liquid column is of sufficient height and the burner E sufficiently low to force the gas to a plane above the service-burners, thus insuring pressure at the burners.

As indicated in Fig. 3 and as stated above, the fuel-supply pipe F of the generator-burner E is in communication with the oil-chamber A above the oil-level, whence it receives a supply of gas as soon as the pipe H' is put into communication with the generator-pipe t', since the pipe H' is in communication, through the medium of the pipe L, with the upper portion of the chamber A.

If the number of service-burners in use corresponds exactly to the capacity of the machine, but small condensation occurs. If, however, fewer burners are in use than will consume the gas being generated, there will be a condensation of the gas in the upper pipes and a return of the gasoline through the channel described to the liquid source or head.

It will be observed that the portion of the apparatus in which the gasoline moves as a liquid is closed, the service-burners being located above the highest possible point reached by the liquid (under the established head or pressure) on a service-pipe constituting, in effect, an extension of the generator-pipe. The location of the generator-burner should be at a sufficient distance below the oil-level (capable of being reached in the generator-pipe when the generator-heater is unlighted) to produce such inequality in pressure between the gas and liquid columns as that the gas will be raised to the desired height and caused to issue at the desired pressure at the service-burner.

While it is believed to be greatly preferable to use the oil column itself for furnish-

ing the pressure of controllable maximum which is depended upon for insuring perfect safety in the use of the machine, yet it is deemed within the spirit of my invention to 5 use other pressure (such as pneumatic) of predetermined maximum for accomplishing the same result. Thus the lower portion of the descending pipe t is to be regarded as an oil-pressure chamber for supplying a determinate 10 pressure to the fluid in the generator-pipe t' capable of supporting in the pipe t' an oil column of a given height, the pipe t' being without communication with the external atmosphere to a plane above that to which the 15 oil can possibly rise under the pressure supplied, thereby removing danger of escape of oil from confinement except as a gas. The pressure means shown is that portion of the apparatus containing the descending oil column—*i. e.*, the oil column above the generator-burner E on the feed side of the machine. Said oil column may be removed and means 20 for supplying pneumatic pressure provided. This is what would occur were the chamber 25 A lowered beneath the level of the burner E and air-pressure supplied. Were the chamber A lowered, so as to preserve a certain head above the burner E , and pneumatic pressure then supplied, it is evident that both liquid 30 and pneumatic pressure would then be used for producing the required gas-pressure.

What I claim as new, and desire to secure by Letters Patent, is—

1. In a gas-generator, the combination of 35 an oil-pressure chamber, a generator-pipe communicating with the lower portion thereof, pressure means of predetermined maximum capable of forcing oil to a given height in said pipe, an extension to said generator-pipe provided with a service-burner above the level to which the oil is capable of being raised by said pressure, and a heater for the generator-pipe at a sufficient distance below the highest possible oil-level in said pipe to afford 40 the desired pressure, said generator-pipe being without communication with the external atmosphere below the level to which the oil is capable of rising therein, substantially in the manner and for the purpose specified.
  2. In a gas-generator, the combination of 45 an oil-pressure chamber, a generator-pipe communicating with the lower portion thereof, pressure means capable of forcing oil to a given height in the generator-pipe, a generator-pipe heater below the highest oil-level in said generator-pipe, a service-pipe, and a valve above said highest attainable oil-level regulating the passage of gas to the service-pipe, said generator-pipe being without orifice below said valve, substantially as and for the purpose set forth.
  3. In a gas-generator, the combination of 55 an oil-chamber, a generator-pipe communicating with the lower portion thereof, a burner for said generator-pipe, a gas-supply pipe for 60 said burner communicating with the upper
- portion of said oil-chamber, a service-pipe, and a pipe-section connecting service-pipe and generator-pipe and in communication with said oil-chamber, and means for regulating the flow of gas, substantially as and for the purpose set forth. 70
4. In a gas-generator, the combination of 75 an oil-chamber, a generator-pipe communicating with the lower portion thereof, a heater for the generator-pipe below the highest attainable oil-level therein, a service-pipe, a pipe-section connecting service-pipe and generator-pipe, a valve between said generator-pipe and said pipe-section above the oil-level, and an air-inlet pipe communicating with said pipe-section adjacent to said valve, said generator being without external orifice below the highest attainable oil-level, substantially as and for the purpose set forth. 80
  5. In a gas-generator, the combination of 85 an oil-chamber, a generator-pipe communicating with the lower portion thereof, a burner for the generator-pipe below the highest oil-level therein, a gas-supply pipe for said burner 90 communicating with said oil-chamber above the oil-level, a valve for the gas-supply pipe, a pipe-section extending above and across said oil-chamber in communication with the upper portion of said chamber, and a valve 95 between said pipe-section and the generator-pipe, substantially as and for the purpose set forth.
  6. In a gas-generator, the combination of 100 an oil-chamber, a generator-pipe communicating with the lower portion thereof, a burner for the generator-pipe below the highest attainable oil-level therein, a gas-supply pipe for said burner communicating with said oil-chamber above the oil-level, a valve for the 105 gas-supply pipe, a pipe-section extending above and across said oil-chamber in communication with the upper portion of said chamber, a valve between said pipe-section and the generator-pipe, an annular ring on the 110 interior of said pipe-section, an induction-pipe of relatively small cross-section adjacent to said valve and having gas-tight connection with said ring, an air-inlet pipe communicating with said pipe-section adjacent 115 to said valve, and a drain-pipe for said pipe-section, between said ring and said valve, said drain-pipe extending beneath the oil-level in said chamber, substantially as and for the purpose set forth. 120
  7. In a gas-generator, an oil-chamber, a generator-pipe communicating with the lower portion thereof, a burner for said pipe below the highest attainable oil-level, a service-pipe, a pipe-section connecting generator-pipe 125 to service-pipe, and in communication with the upper portion of said oil-chamber, a valve between generator-pipe and said pipe-section above the oil-level, and a device for collecting condensed oil and impurities and separating the former from the latter, said device being connected with said service-pipe and 130

the oil-supply in a manner to cause the return of the oil to its source, substantially as and for the purpose set forth.

8. In a gas-generator, the combination of 5 an oil-chamber, a generator-pipe extending above the oil-level of said chamber, a heater for said generator-pipe, a pipe H' in communication with said oil-chamber, a service-pipe, and interposed collecting device connected 10 with the pipe H', comprising elbow l supplied with diaphragm l⁴ and trap l', passage l² communicating with said trap through a perforation l', enlarged pipe or chamber l⁵, inner pipe l³ and drain-pipe l⁶, substantially as and 15 for the purpose set forth.

9. In a gas-generator, the combination of 20 an oil-chamber, a generator-pipe, a burner for the generator-pipe, a gas-supply pipe connecting said burner to said chamber above the oil-level, an oil-reservoir, means for transferring oil to said chamber and for agitating 25 the oil in said chamber, and an extension to said generator-pipe supplied with a service-burner and in communication with the upper portion of said chamber, substantially as and for the purpose set forth.

10. In a gas-generator, the combination of 25 elevated oil-chamber A, a support therefor,

U-shaped pipe C connected with the lower portion of said chamber, generator-burner E 30 provided with chimney D inclosing the rising portion of said U-shaped tube, horizontally-disposed pipe H' supported by and in communication with the upper portion of chamber A, valve G', gas-supply pipe F provided 35 with valve F', and collecting device P, substantially as and for the purpose set forth.

11. In a gas-generator, the combination of 40 an oil-chamber, a vertically-disposed generator-pipe communicating with said oil-chamber and without orifice below the highest oil-level in said pipe attainable under the pressure supplied, pressure means capable of forcing the oil to a predetermined height in 45 said generator-pipe, a generator-burner toward the base of said pipe, a pipe-like chimney inclosing said generator-pipe, means for supplying fuel to the generator-burner, and a service-pipe in communication with the generator-pipe, substantially as and for the purpose set forth.

BERNHARD C. J. ANDERSON.
